UNITED STATES PATENT OFFICE.

ROBERT M. BECK, OF CHAMBERSBURG, PENNSYLVANIA.

DESIGN FOR AN ENGINE-FRAME.

SPECIFICATION forming part of Design No. 17,995, dated January 3, 1888.

Application filed October 27, 1887. Serial No. 253,562. Term of patent 14 years.

To all whom it may concern:

Be it known that I, ROBERT M. BECK, a citizen of the United States, residing at Chambersburg, in the county of Franklin and State of Pennsylvania, have invented and produced a new and original Design for Engine-Frames; and I do hereby declare the following to be a full, clear, and exact description of the invention, such as will enable others skilled in the art to which it appertains to make and use the same.

My invention relates to a newly designed engine-frame; and it consists in the peculiar shape and configuration of the frame, substantially as herein described and claimed.

In the annexed figures of drawings, intended to illustrate my design, Figure 1 is a perspective view of my newly-designed engine-frame. Fig. 2 is a cross section on the line xx of Fig. 1. Fig. 3 is a side elevation, and Fig. 4 is a top plan view.

Similar letters of reference in the different views denote corresponding parts.

In these drawings I have also represented, in addition to the design for a frame which forms the subject of this application, the several mechanical parts of the steam-engine with which the frame is used; but it is not my intention to claim any of these mechanical structures in this case, or even to describe them.

In my new design for an engine-frame, B denotes a vertical plane located above the horizontal base A . D is another vertical plane, which is curved at B' , where it meets the plane B , said plane D being located above the horizontal base A' , which curves to connect with the base A . Thus it will be seen that the plane D , when the engine-frame is viewed from the front, is farther in the rear than the plane B , said planes forming a continuous longitudinal wall above a continuous base whose outer edge or contour is parallel to the surface of said wall.

Members g , g' , and g'' , at right angles to the planes B and D , extend outward toward the edge of the base, the member g being at the left-hand end of the base A , and the member g' being between the planes B and D at their point of meeting and also between the basal

surfaces A and A' at their point of meeting, while the member g'' is at the right-hand end of the plane D and base A' . The surface of plane B is broken centrally by an opening, a .

Surmounting the portion B is a sort of cylindrical figure, C , located horizontally, the left-hand portion, as C' , being seen as completely cylindrical, while the remainder is broken away by a symmetrical outline, so as to leave a sort of semi-cylinder, the right-hand end of which merges into the vertical plane D . The completely cylindrical part C' is straight on its outer edge; but the inner edge is curved, at b , in a line which runs at either end into the parallel lines $c c$, said parallel lines meeting the curved lines $d d$, which recede from the plane of said lines $c c$ along the curvature of the part B' and converge toward each other near the point where the cylindrical figure loses its definiteness in the plane D .

In the rear of the cylindrical figure C is a horizontal tubular part, F , projecting outwardly near the central point of said figure, or adjacent to where the section xx of Fig. 2 is taken.

Many of the minor details in the shape and outline of the design just described may be changed and varied at the pleasure of the person who constructs the engine-frame, and I do not confine myself to these peculiarities; but

What I claim as new, and desire to secure by Letters Patent, is—

1. The design for an engine-frame herein described and shown, the same consisting of the horizontal base having thereupon a vertical plane, a second vertical plane beyond and to the rearward of the first, which it curves at one end to meet, said second plane being likewise on a horizontal base which curves to meet the first-mentioned base, and a cylindrical figure surmounting these vertical planes, one end of the figure being completely cylindrical, while the remainder is broken away by a symmetrical outline which loses its distinctness in the second vertical plane, substantially as described and shown.

2. The design for an engine-frame, as shown and described, consisting of the vertical plane B above the base A , the vertical plane D ,

curved at B' to meet plane B and located above base A', which curves to meet base A, the divisional member g' , and the end members, g and g^2 , the cylindrical figure C, having 5 the complete cylindrical outline C', and the remainder broken away to appear as a part cylinder whose outline consists of the boundary-lines $b\ c\ c\ d\ d$, substantially as shown.

In testimony whereof I affix my signature in presence of two witnesses.

ROBT. M. BECK.
